UNITED STATES PATENT OFFICE.

ALMON W. COPLEY, OF WILKINSBURG, PENNSYLVANIA, ASSIGNOR TO WESTINGHOUSE ELECTRIC & MANUFACTURING COMPANY, A CORPORATION OF PENNSYLVANIA.

MEANS FOR MINIMIZING INDUCTIVE DISTURBANCES.

Application filed August 9, 1916. Serial No. 113,961.

To all whom it may concern:

Be it known that I, ALMON W. COPLEY, a citizen of the United States, and a resident of Wilkinsburg, in the county of Allegheny and State of Pennsylvania, have invented a new and useful Improvement in Means for Minimizing Inductive Disturbances, of which the following is a specification.

My invention relates to means for minimizing or neutralizing disturbances that may be impressed upon electrical circuits by electromagnetic induction from other circuits located in proximity thereto, and it is particularly applicable to the protection 10 of intelligence-transmission circuits, such as telephone and telegraph circuits that, for longer or shorter distances, are located in inductive relation to power circuits which utilize alternating currents.

20 The object of my invention is to provide practical and efficient means of the character above indicated.

When a telephone or telegraph circuit is located in proximity to an alternating-current distributing system, such as a railway system, electromotive forces are induced in the intelligence-transmission circuit that may seriously interfere with its satisfactory operation. In an alternating-current railway system, as the train or propelling vehicle moves from one position to another, a primary circuit, comprising a single turn of varying length, is formed. The electromagnetic field produced by the current flow 30 in this primary turn induces alternating electromotive forces in the adjacent telephone or telegraph circuit. The induced electromotive force depends upon the distance between the intelligence-transmission circuit and the railway or power-transmission circuit, the current-flow in the latter, the variations of the currents obtaining in the power circuit, the lengths of the circuits, and, in the case of a railway circuit, whether 40 the current returns wholly through the track rails or partially through the earth at a greater or less distance from the rails.

According to the present invention, I propose to minimize or neutralize the electromotive forces induced in intelligence-transmission and similar circuits by opposing them with equal and oppositely-directed electromotive forces that are generated by circulating currents in the railway system, the 50 purpose of which is to insure satisfactory

operation of the adjacent intelligence-transmission circuits.

My invention will be more fully explained in connection with the following description and the accompanying drawing, in which Fig. 1 is a diagrammatic representation of a simple system arranged in accordance with my invention; and Fig. 2 is a diagram of a modified form of the system shown in Fig. 1.

Referring to Fig. 1, an electric railway system, which is representative of a suitable power-transmission system, comprises a trolley conductor 1 and a track 2 that are supplied with alternating currents for propulsion purposes from high-tension feeder mains 3. The supply mains 3 are interconnected, at intervals, to the trolley conductor through a plurality of spaced transformers 4 and 5 which are employed usually to reduce the transmission voltage of the feeders to the operating voltage of the railway system. The feeders 3 are connected to any suitable source of power supply (not shown). In proximity to the railway system is an intelligence-transmission circuit 6 represented as a telegraph circuit. The circuit 6 parallels the railway system for a greater or less distance and, therefore, is subject to inductive effects arising from the flow of power currents in the railway system. A second conductor 7, so disposed with respect to the telegraph conductor 6 that it will be subjected to similar or the same inductive influences as are impressed upon the telegraph conductor, parallels the railway system for a greater or less distance and is utilized to furnish the electromotive forces induced in it to indirectly compensate for the disturbing electromotive forces induced in the intelligence-transmission conductor 6.

The power transformer 4 is provided with a secondary winding 8 having a number of taps 9 which are so positioned as to be engaged by the rotatable arm 10 of a power relay 11. The secondary winding 12 of the power transformer 5 is not necessarily provided with taps for adjusting purposes. Under normal operating conditions, the voltage impressed upon the railway system by means of the transformer 4 is equal to the voltage impressed upon the railway system by means of the transformer 5, and, consequently, no circulating currents, other than

power currents, are flowing in the railway system.

The power relay 11, which may be of any usual type adapted for this service, comprises a stationary coil 13, one terminal of which is connected to the trolley conductor 1 and the other terminal of which is connected, by means of a lead 14, to the rotatable arm 10. The power currents, therefore, supplied to the trolley conductor 1, must flow through the current coil 13 of the power relay 11. In the inductive field of the stationary coil 13 is disposed a second coil 15 of the power relay 11. To the coil 15 is attached the rotatable arm 10, both being mounted to rotate about a pivot 16 and the coil 15 being supplied with current through a secondary winding 17 of a transformer 18, the primary winding 19 thereof being connected in series-circuit relationship with the auxiliary or protective conductor 7. Since the primary winding 19 of the transformer 18 is in the circuit of the protective conductor 7 and, consequently, is subject to the flow of currents induced therein by reason of the flow of power currents in the railway system, currents are caused to flow through the movable coil 15 of the power relay 11 that are proportional to the electromotive forces induced in the intelligence-transmission conductor 6. The position of the rotatable arm 10 is, therefore, dependent upon the joint action of the power currents of the railway system and the induced currents flowing in the protective conductor 7.

As above mentioned, under normal conditions, the voltages impressed upon the trolley conductor by means of the transformers 4 and 5 will be such that no neutralizing currents will flow in the trolley conductor. But, when the induced currents in the intelligence-transmission conductor 6, and, therefore, in the protective conductor 7, reach values that are likely to interfere with satisfactory operation, the power relay 11 will selectively engage a particular tap 9 upon the transformer 4 in order to establish a circulating current in the trolley conductor 1 that will induce neutralizing electromotive forces in the intelligence-transmission conductor 6 and in the protective conductor 7. The circulating current will vary, depending upon the current flow in the current coil 13 and the current flow in the movable coil 15 of the power relay 11, the latter current flow being proportional to the disturbing electromotive forces obtaining in the conductors 6 and 7. It will be noted that the power relay 11 is so designed as to be selectively operative for different directions of the alternating-current voltages appearing in the conductor 6. As a result, the circulating currents obtaining in the trolley conductor 1 are made

to flow in the one or the other direction, depending upon whether the load is in proximity to the power transformer 4 or to the power transformer 5. Again, the neutralizing currents flowing in the trolley conductor 1 will be of such value as to substantially preclude the flow of unbalanced disturbing currents in the conductor 6.

In Fig. 2 I have shown my invention employed in connection with a railway system having the trolley conductor and the track rails inductively interlinked by means of booster transformers 35. The trolley conductor 1 is provided, at spaced intervals, with insulating joints 36 across which primary windings 37 of the booster transformers 35 are connected. Secondary windings 38 are connected, through impedance bonds of the usual character 39, to the track 2 and across insulating joints 40 inserted in the track. The booster transformers 35 serve to maintain the return trolley currents in the track circuit, thereby minimizing the zones of disturbing influences that may arise from the flow of the return power currents. The purpose and function of the booster transformers 35 are fully described in a U. S. Patent No. 1,196,300, issued to Charles F. Scott, and assigned to the Westinghouse Electric and Manufacturing Company.

In this system, as hereinbefore described, the high-tension feeder conductors 3 are connected to the trolley conductor 1 by means of spaced transformers 4 and 5, the former being provided with a plurality of taps 9 that may be engaged by a rotatable arm 41 which, in turn, is connected, by means of a conductor 42 and a current transformer 43, to the trolley conductor 1. The transformer 5 is shown as being directly connected to the trolley conductor 1, but it will be understood that the transformer 5 may also be provided with a plurality of taps and associated apparatus, as shown in connection with the transformer 4. The conductor 6 is so disposed as to be influenced by the inductive disturbances arising in the railway system, and the protective conductor 7 is similarly so placed as to be subject also to the inductive disturbances obtaining in the railway system. In the protective conductor 7, a series transformer 44 is inserted, the secondary winding 45 of which, in conjunction with the secondary winding 46 of the transformer 43, serves to influence a power relay device 47. The power device 47 comprises a stationary coil 48 that is connected in closed circuit with the secondary winding 45 and, therefore, generates an inductive action that corresponds to the electromotive forces induced in the protective conductor 7. A rotatable coil 49, to which a contact-making arm 50 is secured, is connected in closed circuit with the secondary winding 46 and, therefore,

generates an inductive action that corresponds to the current supplied to the trolley conductor 1 by the transformer 4. The power device 47 may, when not in its normal position, effect engagement with either the one or the other of adjustable contact members 51 and 52. On effecting engagement between the arm 50 and either of the contact members 51 and 52, a circuit is established for driving a motor 53 that, in turn, operates a worm and wheel mechanism 54 to rotate the arm 41. The motor 53 is furnished with power from mains 55 between which a reversing switch 56 is inserted. The reversing switch 56 comprises solenoids 57 and 58 that are selectively energized by the power device 47. The rotatable arm 50 is connected to one of the supply mains 55, and the common terminal of the solenoids 57 and 58 is connected to the other supply conductor 55. Movement of the arm 50 in the one or the other direction closes the appropriate circuit to operate the reversing switch 56. The position of the switch 56 determines the direction of rotation of the motor 53 and, therefore, the particular tap 9 upon the transformer 4 that is selected to neutralize the disturbances impressed upon the conductor 7. As mentioned above, the amount of circulating current obtaining in the railway system is thus regulated in accordance with the electromotive forces induced in the conductor 6 and the current supplied to the railway system through the power transformer 4.

While I have shown and described several embodiments of my invention, it will be understood that many modifications may be made therein without departing from the spirit and scope of the appended claims.

I claim as my invention:

1. The combination with a conductor of an independent electrical circuit, of an electrical-power-distributing system in inductive proximity thereto, and means influenced by electromotive forces induced in said first conductor for establishing compensating currents in said power system, whereby the inductive effects arising from the flow of power currents therein are substantially neutralized.

2. The combination with an electrical conductor, of an electrical power system positioned in inductive relation thereto and means influenced by the electromotive forces induced in said first conductor and by the load currents flowing in said power system for neutralizing the electromotive forces induced in said first conductor by reason of the load currents in the power system.

3. The combination with a conductor of an independent electrical circuit, of an electrical-power-distributing system in inductive relation thereto which comprises a plurality of conductors that are connected to one an-

other through spaced transformers, said transformers being provided with variable taps and means for varying the taps on said transformers, said means being controlled by the electromotive forces induced in said independent electrical conductor by the currents flowing in the power system.

4. The combination with a conductor of an independent electrical circuit, of an electrical-power-distributing system in inductive relation thereto which comprises a plurality of conductors that are connected to one another through spaced transformers, said transformers being provided with variable taps, and means for varying the taps on said transformers, said means being controlled by the joint action of electromotive forces induced in said independent electrical conductor and the currents flowing in the electrical-power-distributing system.

5. The combination with a conductor of an independent electrical circuit, of an electrical-power-distributing system in inductive relation thereto which comprises a plurality of conductors that are connected to one another through spaced transformers, having variable taps, and means for selectively varying the taps on said transformers in order that proper circulating currents may be established in the distributing system which will neutralize the disturbing electromotive forces induced in the independent electrical conductor.

6. The combination with a conductor of an independent electrical circuit, of an electrical-power-distributing system in inductive relation thereto which comprises a plurality of conductors that are connected to one another through spaced transformers provided with taps, and means for selectively varying the taps upon one of said transformers in order that properly directed circulating currents may be established in the distributing system to neutralize the electromotive forces induced in the independent electrical conductor by the load currents obtaining in the distributing system.

7. The combination with a conductor of an independent electrical circuit, of an electrical-power-distributing system in inductive relation thereto which comprises a plurality of conductors that are connected to one another through spaced transformers having variable taps, and power-relay devices for selectively varying the taps upon one of said transformers in order that currents may be caused to circulate in the power system which will neutralize the inductive effects impressed upon said independent electrical conductor by reason of the load currents flowing in the power system.

8. The combination with a transmission circuit, of a grounded local circuit, a conductor insulated from ground, means for

- connecting said conductor at two different points to said transmission circuit, one of said means including a variable transformer, an independent circuit inductively related to said local circuit, and a power relay device having a coil energized in accordance with the current in said independent circuit and a coil energized in accordance with the current in one of said connecting means.
10. 9. The combination with a power circuit, of a conductor, means for connecting said conductor at two different points to said power circuit, auxiliary means for varying the relative magnitude and direction of the currents in said two connecting means, an independent circuit inductively related to said conductor, and an indicating relay device having a coil energized in accordance with the current in said independent circuit and a coil energized in accordance with the current in one of said connecting means, said device being adjusted to indicate changes required in said auxiliary means in order to minimize inductive interference resulting from currents flowing in said conductor.
10. In a non-inductive interference system, the combination with a pair of power stations, of a power circuit tending to cause inductive interference, means connecting said power circuit at spaced points for interchange of power with the respective power stations, auxiliary means for varying the relative magnitude and direction of the power interchanged between said circuit and the respective power stations, means for producing an electromotive force proportional to the interfering fields which it is desired to eliminate, and an indicating relay device having one coil energized in accordance with said electromotive force and a co-operating coil energized in accordance with the current flowing in one of said connecting means.
11. In a non-inductive interference system, the combination with a pair of power stations, of a power circuit tending to cause inductive interference, means connecting said power circuit at spaced points for interchange of power with the respective power stations, auxiliary means for varying the relative magnitude and direction of the power interchanged between said circuit and the respective power stations, means for producing an electromotive force proportional to the interfering fields which it is desired to eliminate, and an indicating relay device having one coil energized in accordance with said electromotive force and a co-operating coil energized in accordance with the current flowing in one of said connecting means.
12. In a non-inductive interference system, the combination with an alternating-current power circuit, one portion of which tends to set up objectionable static fields in the surrounding ether, of an independent electrical conductor in inductive relationship with the fields set up by the currents in said portion of the power circuit, and means influenced by the electromotive forces induced in said independent electrical conductor for varying the current-flow in said portion of the power circuit.
13. A system as specified in claim 12, characterized by the fact that said means is responsive to both the direction and magnitude of said electromotive forces.
- In testimony whereof, I have hereunto subscribed my name this 20th day of July, 1916.

ALMON W. COPLEY.
